Primary Examiner — Jack Reickel*Assistant Examiner* — Salamah Jordan(74) *Attorney, Agent, or Firm* — Bold IP, PLLC;
 Christopher Mayle(57) **CLAIM**

The ornamental design for a cable machine accessory, as shown and described.

DESCRIPTION

FIG. 1 is a front isometric view of a cable machine accessory, showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in FIGS. 1-6 are for the purpose of illustrating the fastener and form no part of the claimed design.

1 Claim, 4 Drawing Sheets(56)
